US00D915403S

(12) **United States Design Patent** (10) Patent No.: **US D915,403 S**
(45) Date of Patent: **** Apr. 6, 2021**

(54) **MOBILE BIOMETRIC COLLECTION DEVICE**

(71) Applicant: **InCadence Strategic Solutions Corporation**, Manassas, VA (US)

(72) Inventors: **Anthony S. Iasso**, Middleburg, VA (US); **Daniel Iasso**, Towaco, NJ (US); **John P. McIntyre**, Stephens City, VA (US); **Ashley Thompson**, Warrenton, VA (US)

(73) Assignee: **INCADENCE STRATEGIC SOLUTIONS CORPORATION**, Manassas, VA (US)

(**) Term: **15 Years**

(21) Appl. No.: **29/652,223**

(22) Filed: **Jun. 16, 2020**

CLAIM

The ornamental design for a mobile biometric collection device, as shown and described.

DESCRIPTION

FIG. 1 is a bottom front perspective view of a first embodiment of a mobile biometric collection device;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom front perspective view thereof showing broken-line environmental items in use with the mobile biometric collection device.

The broken lines in the figures show environmental structure, and form no part of the claimed design.

1 Claim, 6 Drawing Sheets
